UNITED STATES PATENT OFFICE

2,176,900

METHOD AND APPARATUS FOR PICKLING COILS

Agnes Jane Reeves Greer, Morgantown, W. Va.

Application August 6, 1938, Serial No. 223,494

15 Claims.

(Cl. 148—8)

The invention relates to the pickling of coils of strip steel and the like and more particularly to certain improvements upon the general method of pickling disclosed in my Patent No. 5 2,091,921 issued August 31, 1937, Shoemaker Patent No. 2,120,843, issued June 14, 1938, and my pending application Serial No. 203,507, filed April 22, 1938.

In the general method of pickling disclosed in 10 the above patents and application, coils of metal strip material are supported upon mandrels, which are rotated as they are progressed through the pickling and washing solutions, whereby the coils are in turn rotated through the solution 15 by the mandrels.

This rotation of the coils may be continuously in a forward direction as disclosed in the above mentioned patents or may be alternately forward and backward or continuously backward 20 as the mandrels are carried forwardly, as shown in my pending application above referred to.

It has been found that the pickling action is increased by rocking or oscillating the coils forwardly and backwardly upon the mandrels as 25 they are rotated upon the same and progressed through the pickling solution, and the object of the present improvement is to provide a method and apparatus for rocking or oscillating the coils upon the mandrels at the same time that the 30 coils are rotated and moved forward through the pickling solution, this rocking or oscillating movement of the coils producing a pumping action which alternately and successively pumps the pickling solution through all portions of each 35 coil, between the convolutions thereof so as to speed up the pickling operation.

This rocking or oscillation of the coils upon the mandrels while the same are being rotated may be accomplished by many different types of apparatus for producing the desired result, but for 40 the purpose of illustration a simple mechanism is provided for accomplishing this result.

In the accompanying drawings

Figure 1 is a longitudinal sectional elevation 45 through the pickling tank and associated mechanism of a pickling machine of the general type to which the invention is applicable, showing the mechanism cooperating therewith for rocking or oscillating the coils as they are rotated upon 50 the mandrels and carried through the pickling solution;

Fig. 2, an enlarged side elevation of one of the coil rocking devices showing the manner in which the coil is rocked or oscillated to pump the pickling solution therethrough; and

Fig. 3, a sectional elevation taken as on the line 3—3, Fig. 2.

Similar numerals refer to similar parts throughout the drawings.

The loosely wound coils of strip metal to be 5 pickled as indicated at 10 are received upon the storage platform 11 and held by the stop 12 in the manner disclosed in the patents above referred to until such time as the stop 12 is operated for swinging the same upon its pivot 13 to 10 permit the coil to roll onto the top of said stop member so that a mandrel as indicated generally at 14 may be inserted through the coil and received upon the inclined rails 15, thus supporting the coils upon the mandrel and as 15 the stop 12 is moved backward to the position shown in Fig. 1 the mandrel may be received in the hooked upper ends 16 of the charging arms 17 supporting the coil in position to be charged into the pickling tank 18 at the desired time. 20

All of the above mechanism may be constructed and operated in the manner shown in the Greer and Shoemaker patents above referred to and as this charging mechanism forms no part of the present invention it is not thought necessary to further describe the same in detail. 25

The pickling tank 18 may be provided with the rails 19 along its upper edges forming a track upon which the mandrels may be rotated throughout the length of the tank so that the 30 coils suspended thereon may be rotated, preferably, partially submerged in the acid.

As illustrated and described in the patents and application above referred to, the sprockets 20 upon the mandrels may be engaged by the endless drive chain 21 for rotating the mandrels and moving them forwardly along the track 19, 35 rotating the coils suspended therefrom through the pickling acid.

Sprocket wheels 22 are located at opposite ends 40 of the pickling tank 18, the drive chain 21 being located over said sprocket wheels and continuously driven in unison as by means of gearing indicated generally at 23 and the motor 24 for driving the chain 21 in the direction of the arrows shown in Fig. 1. 45

For the purpose of controlling the operation of the charging arms 17 so as to prevent the same from delivering a coil into the pickling tank before the preceding coil has progressed the desired distance through the tank, a control mechanism as disclosed and claimed in the Shoemaker patent above referred to, is provided for controlling the operation of the charging 50 mechanism.

motor 25, this controlling mechanism being indicated generally at 26 in Fig. 1.

The coils may be continuously rotated in a forward direction as the mandrels are progressed forwardly through the pickling tank as disclosed in my prior patent and the Shoemaker patent, or if desired, as shown in Fig. 2, the coils may be alternately rotated in opposite directions as the mandrels progress forwardly through the 10 pickling tank by means of the chain 63 of a reversing mechanism as disclosed in my co-pending application above referred to, the coils being simultaneously rotated and rocked or oscillated as will be hereinafter described in detail 15 in carrying out the improved method to which the invention pertains.

Various means may be provided for rocking the coils forward and backward upon the mandrels, but, for the purpose of illustration a mechanism is 20 shown carried upon a spaced pair of elliptic channel members 27 which may be supported above the pickling tank in any suitable manner.

An endless chain 28 is located around the outside of one of these elliptic channel members 25 and arranged to be driven in the direction of the arrow shown in Fig. 1 by means of a sprocket 29 mounted upon a short shaft 30 upon which is located a smaller sprocket 31 connected by the chain 32 with a sprocket 33 upon the gear reduction 34 which is driven as by the motor 35.

A plurality of rocking forks is connected to the chain 28 and arranged to be driven thereby, these forks being located at uniform distances apart and so spaced and moved that each coil as it enters the pickling bath will be engaged by one of the forks and will be rocked forward and backward as it is carried through the pickling solution.

Each fork is carried upon a carriage 36 having 40 four flanged wheels 37, two of which travel in each of the elliptic channel members 27. A lever 38 is pivoted as at 39 upon each carriage and is provided at its lower or outer end with the T head 40 upon which the fork proper is carried.

This fork may be in the form of a curved bar 41 45 pivoted intermediate its ends as at 42 upon the T head 40 and provided at each end with the leaf spring arms 43 spaced so as to engage a coil therebetween.

The fork may be cushioned as by the coil springs 50 44 interposed between the end portions of the T head 40 and the bar 41, a bolt carried by the bar being located through each spring and through a suitable opening in the T head 40 and provided with a head or nut 45.

For the purpose of rocking the fork, as shown 55 in full lines and broken lines in Fig. 2, a connecting rod 46 may be pivoted at one end to the inner end of the lever 38, as shown at 47, and at its other end to a disk 48 mounted upon a shaft 60 49 and journaled through a portion of the carriage 36, a sprocket 50 being fixed upon the other end of said shaft and arranged to mesh with the endless chain 51, which is located over suitable sprockets 52 carried at opposite ends of the 65 frame 53.

A shaft 54 of one of the sprockets may have another sprocket 55 mounted thereon and connected by the chain 56 with a sprocket 57 driven through the gear reduction 58 as by a motor 59 70 in the direction of the arrows, shown in Figs. 1 and 2.

Each of the carriages 36 is connected to the chain 28 as by a depending lug 60 and a pin 61 so that the carriages will move in uniformly spaced 75 relation around the elliptic tracks 27, and at a

speed timed with the speed of the mandrels carrying the coils through the pickling tank.

As each coil suspended upon a mandrel is entered into the pickling tank, the coil will be engaged by one of the forks which will move with the coil through the pickling tank.

The chain 57 being driven in a direction opposite to the movement of the forks, will, through the sprocket 50, disk 48 and connecting rod 46 rock the fork between the positions shown in full lines and broken lines in Fig. 2, alternately rocking or swinging the coil forward and backward upon the mandrel as shown in said figure.

As the coil is rocked forward, as shown in full lines in Fig. 2, the convolutions upon the rear side of the coil will be compressed and those upon the forward side of the coil expanded forcing the pickling acid from between the compressed convolutions causing it to rapidly flow between the expanded convolutions.

On the reverse movement of the fork, this action is reversed and as the coil is alternately rocked forward and backward as it is rotated and progressed through the pickling tank, the acid will be continuously pumped through all portions of the coil, thus, speeding up the pickling operation and producing a more effective pickling of the coils.

As each coil moves to the discharge end of the pickling tank, it will pass out of engagement with the fork, which will be carried up and over the elliptic frame, the coil passing to the dotted line position, shown at the right hand side of Fig. 1, and then into the transfer arms 62 by means of which the mandrel with the coil suspended thereon may be removed from the pickling tank and transferred to a washing tank as disclosed in the prior patents above referred to.

I claim:

1. The method of pickling a coil of metal which consists in suspending the coil and rotating the coil around the point of suspension and moving it forward in a bath of pickling fluid and alternately contacting the coil on opposite sides for rocking the coil forward and backward in the fluid relative to its point of suspension so as to alternately compress and expand the convolutions on opposite sides of the coil in order to pump the pickling fluid therethrough.

2. The method of pickling a coil of metal which consists in suspending the coil and progressively moving the coil forwardly within a bath of pickling fluid and rotating the coil backwardly as it is progressed forwardly through the fluid, and rocking the coil forward and backward in the fluid relative to its point of suspension so as to alternately compress and expand the convolutions on opposite sides of the coil in order to pump the pickling fluid therethrough.

3. The method of pickling a coil of metal which consists in suspending the coil and progressively moving the coil forwardly within a bath of pickling fluid and rotating the coil alternately forward and backwardly as it is progressed forwardly through the fluid, and rocking the coil forward and backward in the fluid relative to its point of suspension so as to alternately compress and expand the convolutions on opposite sides of the coil in order to pump the pickling fluid therethrough.

4. The method of pickling a coil of metal which consists in suspending the coil and rotating the coil around its point of suspension and moving it forward partially submerged within a bath of pickling fluid and alternately contacting the coil on opposite sides for rocking the coil forward and

backward in the fluid relative to its point of suspension so as to alternately compress and expand the convolutions on opposite sides of the coil in order to pump the pickling fluid therethrough.

5. The method of pickling a coil of metal which consists in suspending the coil and moving it forward within a bath of pickling fluid and alternately contacting the coil on opposite sides for 10 rocking the coil forward and backward in the fluid relative to its point of suspension so as to alternately compress and expand the convolutions on opposite sides of the coil in order to pump the pickling fluid therethrough.

15. Pickling apparatus for pickling a coil of metal including a tank containing liquid, a mandrel upon which the coil is suspended in the liquid, means for rotating the mandrel whereby the coil is rotated, and means movable in unison with the mandrel and moving relative to the coil for intermittently contacting the coil for rocking the coil upon the mandrel.

20. 7. Pickling apparatus for pickling a coil of metal including a tank containing liquid, a mandrel upon which the coil is suspended partially submerged within the liquid, means for rotating the mandrel whereby the coil is rotated, and means movable in unison with the mandrel and moving relative to the coil for intermittently contacting the coil for rocking the coil upon the mandrel.

25. 8. Pickling apparatus for picking a coil of metal including a tank containing liquid, a mandrel upon which the coil is suspended, means for moving the mandrel along the tank and rotating the mandrel whereby the coil is rotated and moved forward through the liquid, and means movable in unison with the mandrel and moving relative to the coil for intermittently contacting the coil for rocking the coil forward and backward upon the mandrel as it is moved through the liquid.

30. 9. Pickling apparatus for pickling a coil of metal including a tank containing liquid, a mandrel upon which the coil is suspended, means for moving the mandrel along the tank whereby the coil is moved forward through the liquid, and means movable in unison with the mandrel and moving relative to the coil for intermittently contacting the coil for rocking the coil forward and backward upon the mandrel as it is moved through the liquid.

35. 10. Pickling apparatus for picking a coil of metal including a tank containing liquid, a man-

drel upon which the coil is suspended, means for moving the mandrel along the tank and rotating the mandrel whereby the coil is rotated and moved forward through the liquid, a fork arranged to engage the coil, means for moving the fork in unison with the coil, and means for oscillating the fork for rocking the coil forward and backward upon the mandrel as it is moved through the liquid.

40. 11. Pickling apparatus for picking a coil of metal including a tank containing liquid, a mandrel upon which the coil is suspended, means for moving the mandrel along the tank and rotating the mandrel whereby the coil is rotated and moved forward through the liquid, an endless chain above the tank, means for moving the chain in unison with the mandrel, a fork upon the chain arranged to engage the coil, and means for oscillating the fork for rocking the coil forward and backward upon the mandrel as it is moved through the liquid.

45. 12. Pickling apparatus for pickling a coil of metal including a tank containing liquid, a mandrel upon which the coil is suspended within the liquid, means for rotating the mandrel whereby the coil is rotated, and means movable relative to the mandrel for striking the coil to rock it upon the mandrel.

50. 13. Pickling apparatus for picking a coil of metal including a tank containing liquid, a mandrel upon which the coil is suspended within the liquid, means for rotating the mandrel whereby the coil is rotated, and means movable relative to the mandrel for striking the coil on opposite sides to rock it upon the mandrel.

55. 14. The method of picking a coil of metal suspended on a mandrel in a bath of pickling fluid, which consists in rotating the coil upon the mandrel, and rocking the coil forward and backward in the fluid relative to the mandrel so as to alternately compress and expand the convolutions on opposite sides of the coil in order to pump the pickling fluid therethrough.

60. 15. The method of pickling a coil of metal suspended on a mandrel in a bath of pickling fluid, which consists in rotating the coil alternately in opposite directions upon the mandrel, and rocking the coil forward and backward in the fluid relative to the mandrel so as to alternately compress and expand the convolutions on opposite sides of the coil in order to pump the pickling fluid therethrough.

AGNES JANE REEVES GREER.
